UNITED STATES PATENT OFFICE

170,473

CLOTHESHORSE

Carl Allen Nelson, Whittier, Calif.

Application April 6, 1953, Serial No. 24,359

Term of patent 14 years

(Cl. D33—8)

To all whom it may concern:

Be it known that I, Carl Allen Nelson, a citizen of the United States of America, residing at Whittier, in the county of Los Angeles and State of California, have invented a new, original, and ornamental Design for Clotheshorse, of which the following is a specification, reference being had to the accompanying drawings, forming a part thereof.

Fig. 1 is a perspective view of a clotheshorse showing my new design; and

Fig. 2 is a rear elevational view thereof.

I claim:

The ornamental design for a clotheshorse, as shown.

CARL ALLEN NELSON.
